UNITED STATES PATENT OFFICE.

DAVID F. DAVIDS, OF NEW YORK, N. Y.

DESIGN FOR A BOTTLE.

SPECIFICATION forming part of Design No. 23,274, dated May 15, 1894.

Application filed April 13, 1894. Serial No. 507,463. Term of patent 7 years.

To all whom it may concern:

Be it known that I, DAVID F. DAVIDS, of New York city, in the county of New York and State of New York, have invented and 5 produced a new and original Design for Bottles; and I do hereby declare the following to be a full, clear, and exact description of said invention, reference being had to the accompanying drawings, and to the letters of reference marked thereon, which form a part of 10 this specification.

My design is for the shape of a bottle.

Figure 1 is a side view of my design and Fig. 2 is a bottom view, these two views being deemed necessary to fully illustrate my 15 design.

The leading feature of my design consists in a curved concave surface to the sides of a four-sided bottle A., and an extension of corners on a square base B. Also, a pear shaped 20 contour of the bottle, and a ring at junction of base of neck and top of shoulder, with a panel for a label.

What I claim is—

The design for a bottle as herein shown and 25 specified.

In testimony whereof I affix my signature in presence of two subscribing witnesses.

D. F. DAVIDS.
